UNITED STATES PATENT OFFICE.

ALBERT E. NEWTON, OF WORCESTER, MASSACHUSETTS, ASSIGNOR, BY MESNE ASSIGNMENTS, TO REED-PRENTICE COMPANY, OF WORCESTER, MASSACHUSETTS, A CORPORATION OF MASSACHUSETTS.

ATTACHMENT FOR TURNING MULTIPLE-DIAMETER SHAFTS.

1,118,875.

Specification of Letters Patent.

Patented Nov. 24, 1914.

Application filed February 28, 1908. Serial No. 418,216.

To all whom it may concern:

Be it known that I, ALBERT E. NEWTON, a citizen of the United States, residing at Worcester, in the county of Worcester and State of Massachusetts, have invented a new and useful Attachment for Turning Multiple-Diameter Shafts, of which the following is a specification.

This invention relates to an attachment for turning multiple diameter shafts, and has been especially designed for duplicate work.

Many shafts which are used in machine work are turned to have various diameters, such as a small diameter at one end increasing by steps up to the other end or to an intermediate part of the shaft. It is often desired to make up a large number of such shafts. The attachment is designed to be applied to an ordinary or improved form of lathe for these purposes.

The attachment comprises a peculiar form of rest upon which a number of blocks are mounted, each of which blocks carries a turning tool. Each block is also provided with a support which can be swung up and down and can be locked in its lowest or operative position, which support carries rolls forming supports for the work. This construction is used with a cut-away form of tail stock arranged so that the blocks can be run past the tail stock and the tools brought into operation, one after the other. Means are provided so that the tools can be adjusted lengthwise relatively to each other and also so that each tool can be adjusted relatively to the work arranged so that when these adjustments are once made, they can be kept for duplicate work. In the preferred form of structure, the lathe is arranged to run backward as compared with the usual operation and the blocks are placed on the rear arm of the rest. The tail stock block is cut away or recessed on its back side so that the long arm of the rest which carries the blocks can pass the tail stock. By this attachment, the results above specified can be easily accomplished.

The invention is illustrated in the accompanying two sheets of drawings forming part of this application, referring to which,

Figure 1 is a front elevation showing the improved attachment. Fig. 2 is a diagram-

matic view illustrating the work produced. Fig. 3 is a side elevation of the improved form of tail stock. Fig. 4 is a cross sectional view taken on the line 4—4 of Fig. 3. Fig. 5 is an end view of part of one of the blocks and of the tail stock. Fig. 6 is a plan of the peculiar form of rest which is used. Fig. 7 is an end elevation of one of the improved blocks showing the support carried thereby. Fig. 8 is a plan thereof. Fig. 9 is a detail of the locking means for holding the tool in place in the block, and Fig. 10 is a front elevation of the rest and blocks mounted thereon.

Referring to the drawings and in detail, A designates the lathe bed mounted on the end of which is any of the usual headstocks B.

C designates the apron which is secured to the front of the rest D.

The lathe is provided with the usual lead-screw or feed-shaft 10 and also with a feed-rod 11 which parts engage suitable mechanism in the apron so that the rest can be fed along the ways of the lathe in the usual way. A collar 12 is adjustably secured on the rod 11 and the same forms an adjustable throw-out mechanism for limiting the left-hand or feed movement of the rest. A face plate 13 is screwed on the end of the spindle in the head stock in the ordinary manner and a key 14 is arranged between the spindle and face plate so that the power can be taken through the face plate with the lathe running backward without unscrewing the face plate from the spindle. The usual center 15 is placed in the head stock spindle. By this arrangement, the work can be turned backward as compared with the ordinary lathe.

The construction of the tail stock is indicated more particularly in Figs. 3, 4 and 5. The tail-stock consists of a plate 16 which is fitted to slide on the inside ways of the lathe bed. Fitted to slide laterally on said plate 16 is the tail-stock block 17. The block 17 is adjustable on the plate by screws 18. A binder 19 is fitted under the lathe ways and is connected to the block by a shaft 20 which has an adjustable nut on the end thereof. The top of the shaft 20 is bored out and fitted into the same is an eccentric formed on a shaft 21 journaled in the

block 17, which shaft 21 is provided with a handle 22. By manipulating this handle 22, the tail stock can be secured to the bed in adjusted position. It will be noticed that the tail-stock block 17 is so formed on its rear side so that the tool blocks hereinafter described can pass by the same, as shown in Fig. 5. Fitted in the tail-stock block is a spindle 23 which has a depending arm engaging between collars formed on a screw 24 threaded into the block 17 and having a handle 25 by turning which the spindle can be adjusted. The tail-stock center 26 works in a barrel or hub 27 projecting from the block 17 and the center is made of the same diameter as the spindle. The center has a screw-threaded end which is threaded into the end of the spindle 23. The center is grooved and engaging the groove is a screw 28 which allows the center to move axially but prevents the same from turning. The end of the center is flattened so that a wrench can be put on the same. The center is applied in position when the screw 28 is withdrawn by threading the same into the spindle and then when in position, the screw 28 is screwed in to engage the groove. To hold the center in its adjusted longitudinal or axial position, a split bushing 29 is dropped into a hole bored in the barrel or hub 27. This bushing is cut away so that the center can pass through the same, as shown in Fig. 4. A bolt 29 is passed through the bushing and a knurled handle 30 is threaded on the end of the bolt whereby by tightening the handle, the two parts of the bushing will be brought closer together to pinch on the center and hold the same tightly in the barrel or hub 27. The center 26 has a groove 31 formed in the same, as shown, so that the tool T can move longitudinally in the same which is useful when the final cut made in the lathe is to be such that the smallest diameter of the shaft will be less than the diameter of the center. It also will be noticed that the tail-spindle 23 is made substantially the same diameter throughout its length as the center 26 and that the block 17 is cut away so that the spindle 23 and center 26 are exposed on the rear side of the block. The spindle 23 is also provided with a slot 310 coinciding longitudinally with the slot 31 in the center so that the tool can pass along the spindle as well as the center when the adjustment of the tool or tools is made for a very small diameter on the work or shaft to be turned.

The rest D is shown in plan view in Fig. 6. The same consists of a front arm 32, a cross arm 33 and a long rear arm 34. It will be seen that the arms 32 and 34 extend entirely to one side of the cross arm 33. The rear arm 34 is shaped and elevated so as to clear the plate 16 of the tail-stock as indicated in Fig. 5. The cross arm 33 may be provided

with the usual ways and a tool block 35 may be adjustably mounted thereon so that if desired, the lathe can be used for ordinary turning purposes. The arms 32 and 34 have grooves formed in the under surfaces thereof to engage and fit on the outer ways or V's of the lathe bed. The rear arm 34 is provided with a dovetail projection 36 on which the improved tool blocks hereinafter described are adjustably mounted. The tool blocks are the same as hereinafter described and each is constructed substantially as follows:—Fitted on the dovetail 36 is a base piece 37 which has a gib 38 which may be tightly screwed against the dovetail 36 by screws 39. By loosening the screws 39, the base piece 37 can be adjusted in any position desired longitudinally on the rear arm 34 whereby the tool blocks can be set accurately relatively to each other for the purpose hereafter described. By tightening the screws 39, the base piece is rigidly secured in position. The base piece is provided with a dovetail 40 fitted to slide on which is a block 41. An adjusting screw 42 is arranged in the base piece 37 and engages a nut 43 secured to the block 41, the screw being held in place by a small plate attached by screws to the front face of the base piece 37, as indicated in Fig. 7. By this arrangement, the block 41 can be adjusted longitudinally on the base piece 37 to adjust the tool T to the work. The adjustment needed for this purpose is small and the same will not usually affect the action of the supporting rollers hereinafter described. The block 41 is provided with a supplemental piece or part 44 attached thereto by screws 45. Slots 46 are formed between the block 41 and the block cover 44 which slots are adapted to receive the turning tools T. The block 41 is made with the cover 44 so that these slots can be accurately planed. These slots are shaped to just about the size to receive the tool. There may be two slots in each block, as shown in the outer blocks, or three slots, as shown in the inside blocks in Fig. 10 so that the tools can be placed relatively as close or far apart from each other as desired to meet the exigencies of the work. The top of each slot 46 is cut away on a taper, as shown more particularly in Fig. 7. Threaded into the block 41 is a screw 47 which extends through the block and is provided with a head on its front end which can be manipulated by a wrench. Fitted to the taper of each of the slots is a taper-key or piece 48, as shown in detail in Fig. 9. This key has an extending arm 49 which fits between collars formed on the screw 47 whereby by manipulating said screw by a suitable wrench, the taper-key may be moved forward and thus forcibly pressed downward to engage and lock the tool T in position. By this arrangement, the

tool may be very powerfully and quickly clamped in substantially its proper position. A dovetail 50 is formed on the top of the member 44 and fitting the same is a block 51 which is held in place on the dovetail by a gib 52 which is tightened by screws 53 passing through the block 51 and threaded into said gib. By this arrangement, the block 51 is adjustable on the part 44 and can be clamped in its adjusted position by tightening screws 53, so that when necessary the position of the supporting rollers hereinafter described may be adjusted. The top of the block 51 has an L-shaped slot 54 planed in the same, as shown in Fig. 10. A roller support 55 having a cross section, as indicated in Fig. 10, is fitted in said slot and is pivoted on a pin 56 driven through the sides of the block 51 so as to pass through the slot. The roller support 55 is provided with a projection or arm 57 which fits into the horizontal part of the L-shaped slot 54 in the block. The support 55 is not made as wide as the slot by the thickness of this part so that when the support is moved to the left, as shown for example at the second block counting from the left in Fig. 10, the support can be moved up out of the slot 54, but so that when the support is moved to the right, as shown at the third block counting from the left in Fig. 10, the part 57 will engage in the horizontal portion of the L-shaped slot and will thus be securely locked in position. It also will be noticed that this locking movement of the support is toward the right or in the contrary or opposite direction to the feed so that any drag on the supporting rollers hereinafter described will tend to keep the support more firmly in the L-shaped slot. The right-hand end of the slot is counter-bored around the pin 56 and a spring is placed therein, as shown in Fig. 8, which spring will normally tend to force the support to the position shown on the second block as above numbered, so that the same normally is in position to be turned about the pin 56. To lock the support in its right-hand position, a shaft 58 is journaled in the block and is provided with an eccentric 59 which engages the left-hand face of the support 55. A handle 60 is secured on the end of this shaft and by turning this handle, the support can be powerfully forced to the right and into locking position in the L-shaped slot. When it is desired to turn up the support, the handle is moved to release the eccentric 59 from engagement with the support 55. The support 55 is extended out around the work as shown in Fig. 7 and is provided with ways 61 preferably on both sides thereof in which are fitted sliders 62 which are yoked at their lower ends and which carry pins on which are mounted rollers 63. The sliders are adjusted by screws 64 threaded in projections formed on the support and are clamped in position by screws 65 passing through slots in the support and threaded into the sliders. The ways 61 are preferably formed on both sides of the support 55 so that the sliders can be placed on either side of the support 55 to come approximately in any desired position on the shaft S which is being turned, the heads on the screws 65 being made wide so that the same will fit down into the slots, as indicated in Fig. 8. It is usually the practice to provide two screws 64 in each support for each slider so that the sliders can be quickly shifted from one side to the other of the support. By this construction, the rolls can be set accurately to the work and can be held in their clamped positions.

The operation is substantially as follows:—A dog is placed on the work in the usual way which dog is engaged with the face plate 13. The tail-stock and center are then adjusted so that the work will be held on the centers. The supports 55 are turned up and the lathe rest is run to the extreme right so that the left-hand tool will clear the right-hand end of the work. The tool blocks are adjusted longitudinally accurately on the rear arm 34 of the rest so that they will be a distance apart equal to the length of the various diameters it is desired to give to the shaft. The tools are then, as they come into position, adjusted accurately crosswise of the lathe so that they will give the exact diameters desired for the various sections of the shaft. Suppose it is desired to turn a shaft to have four steps of different diameters and of the lengths shown in Fig. 2, the tools are then adjusted as indicated. As the lathe is put into operation the left-hand tool will first engage the work and reduce the same to the size for which it is set. The second tool will next engage the work and then the third and the fourth tool, the tools coming into operation one after the other and the succeeding tools acting on the diameter left by the previous tools. Thus in the illustration in Fig. 2 the left-hand bearing of the shaft will have been turned by one tool, the second by two tools, the third by three tools, and the fourth by four tools. As the tools successively come into operation, the bearing pieces 55 are swung down and locked in their operative position so that the rollers 63 will engage the work just behind or to the right of each tool whereby the shaft will be accurately supported independently of its centers so that powerful heavy cuts can be taken on the same without liability of springing. When the rest stops at its left-hand position, the shaft will have been turned at one operation to the condition shown in Fig. 2. The left-hand unfinished end of the shaft can be turned at a separate operation or if the work demands, the work

can be turned around and various steps or bearings turned thereon, as indicated in dotted lines in Fig. 2, by another adjustment and operation of the lathe. Thus the 5 shaft can be turned to the condition shown in Fig. 2 at one operation and one feed movement of the lathe. When one piece is turned and the proper adjustment of the tools thereby necessarily made; duplicate 10 pieces can be quickly produced. When the shaft is turned, the same is taken out of the lathe, the supports 55 turned up, the rest run to its extreme right-hand position, a new piece of work inserted, and the operation repeated thereon. The next turning operation will require no adjustment of the tools and thus duplicate shafts having 15 multiple diameters can be produced in quantity very expeditiously and cheaply.

20 The rest, tool blocks, and tail-stock herein shown and described may be sold as an attachment for an ordinary lathe and as many tool blocks may be applied on the rest as can be fitted thereon or as the particular kind of work to be done demands.

Many of the parts and constructions herein shown and described may be used in other forms of lathes and for other purposes than for that herein described.

30 The device herein shown and described may be greatly varied by a skilled mechanic without departing from the scope of my invention as expressed in the claims.

Having thus fully described my invention, what I claim and desire to secure is—

1. In a lathe attachment for turning multiple diameter shafts, a bed having ways thereon, a rest having parallel front and rear arms each resting on one of said ways, 40 a number of tool blocks longitudinally adjustable on the rear arm, means whereby the tool blocks can be locked and longitudinally adjusted relatively to each other, and means whereby each tool block carries a tool which 45 can be adjusted longitudinally.

2. In a lathe attachment for turning multiple diameter shafts, the combination with a bed having level ways thereon, of a rest having parallel front and rear arms, each 50 resting on one of said ways, a plurality of tool blocks mounted on the rear arm, a tail-stock block centrally supported on the ways and recessed or cut away on its rear side, and a spindle carried thereby and exposed 55 by the recess and having a longitudinal re-

cess registering with the recess of the tail-stock block, so that the tools can pass back of the same.

3. A tail stock having a block cut away on one side, a spindle fitted therein, and a center carried by the spindle, the block being cut away so that the spindle and center are exposed along one side and the spindle and center each having a longitudinal recess whereby a tool which is adjusted close to the center line of the lathe can pass the tail stock.

4. The combination of a lathe rest having a rear arm, a tail-stock comprising a plate and a block slabbed or cut away on its rear side, the rear arm of said slide being shaped and elevated to pass over the plate and to clear the block of the tail-stock.

5. A lathe rest having a front arm, a cross arm, and a rear arm, the front and rear arms extending entirely to one side of the cross arm and tool blocks mounted on the rear arm.

6. The combination of a lathe rest comprising a front arm, a cross arm, and a rear arm, the rear and front arms extending entirely to one side of the cross arm and the rear arm being longer than the front arm and a tail-stock in line with the front arm and out of line with the rear arm, whereby the end of said rear arm can pass by the tail-stock.

7. In a lathe attachment for turning multiple diameter shafts, the combination of a rest having a long arm, a number of tool blocks mounted thereon, a support carrying rollers pivoted to each block, which roller supports can be turned up so that the blocks can be moved past the tail-stock.

8. In a lathe attachment for turning multiple diameter shafts, the combination of a rest having a long arm, a plurality of tool blocks secured thereto, a support pivoted to each tool block and carrying a number of rollers, and a tail-stock having a block cut or slabbed away, the whole so arranged that the blocks can be moved past the tail stock by moving the roller supports.

In testimony whereof I have hereunto set my hand, in the presence of two subscribing witnesses.

ALBERT E. NEWTON.
